BALL GAME DEVICE

Omey M. Monkres, Long Beach, Calif., assignor
of fifty per cent to Arthur Peter Smith, Long
Beach, Calif.

Application November 6, 1947, Serial No. 784,364

8 Claims. (Cl. 273—121)

1

This invention relates to improvements in ball game devices, and more particularly to amusement devices of the character in which a missile, such as a ball, is directed and propelled toward a target area by a person playing the game, and is of the character commonly termed "pin-ball" games.

An object of this invention is to improve the construction of such games, to increase the interest thereof, by producing novel and unusual effects thereby.

Another object of this invention is to provide a game device which a multiplicity of persons can play and which game device automatically traps the remaining missiles which are not in playing position upon the completion of the game by one of the players.

A further object of the invention is to operate a game of the character described by propelling a missile into the target area, and to create thereby an effect simulating a game of playing cards, such as a game of poker, the results simulating various poker hands of cards and being counted in like manner.

The invention may be constructed, according to one embodiment, by the provision of a target or playing field, including a table or area simulating a plurality of card game indicia, such as the suits of a standard deck of playing cards, which indicia have a plurality of holes therethrough, respectively, through one or another of which the ball or other missile may find its way to energize scoring means electrically actuated and having a number of signalling elements which may correspond respectively with playing card scoring characters, whereby a novel and attractive arrangement of these parts is produced, whereby the game may be won in different ways, as indicated by the respective signalling devices.

According to this embodiment, a playing table is used having provision for the projection of a ball or other missile into a target area, which target area preferably contains indicia representing the respective suits of a deck of playing cards, such as "spades," "diamonds," "clubs" and "hearts." A plurality of orifices, representing the respective rank of the playing cards, are provided adjacent each of the suit indicia, which said orifices are in position to receive the projected ball therethrough. Suitable obstructions are provided in the path of the ball or missile, such as a plurality of pins upstanding from the surface of each of the indicia. Provision is made whereby the ball, in dropping through the hole,

2

will close an electric switch, which in turn completes a circuit through an indicator, such as a light on the backboard, and through a relay connected in the circuit, which relay carries a multiplicity of contact points which are adapted to close a portion of each of a plurality of circuits, which are indicated as three in the present instance, so as to give various winning combinations as result of the plays. The electrical indicator, having suitable provisions for indicating through signalling devices the corresponding cards, will accumulate the results of suitable combinations as a result of a series of successfully propelled missiles so as to constitute a game, whereby the result of the score produced thereby is indicated on the signalling device or annunciation. Several such game devices may be associated with each other and played one against the other for comparing the results produced thereby by different players.

This embodiment of the invention is illustrated in the accompanying drawings, in which:

Fig. 1 is a perspective view of a plurality of game devices associated with each other for comparable action by different players;

Fig. 2 is a perspective view of one of the game tables detached;

Fig. 3 is a similar view of one of the backboards, shown in open position and with a part broken away for clearness of illustration;

Fig. 4 is a perspective view of one of the indicator shields;

Fig. 5 is a sectional view through a portion of the table showing the circuit closing means thereof;

Fig. 6 is a bottom plan view of the circuit closing means;

Fig. 7 is a top plan view of a portion of the table showing the ball trap;

Fig. 8 is a sectional view through the table, and with parts broken away and shortened in order to show the details of construction;

Fig. 9 is a perspective view of the multiple-point relay;

Fig. 10 is a sectional view taken on the line 10—10 of Fig. 9, looking in the direction indicated by the arrows;

Fig. 11 is a diagrammatic, pictorial illustration of the electrical wiring as associated with the table and the backboard; and

Fig. 12 is a schematic wiring diagram showing the various relays and contacts for closing the various circuits.

The invention is illustrated in Fig. 1 with a plurality of game devices associated with each

other and supported on an elongated counter, generally indicated at 1, adapted for playing action by respective players. Each of the game devices comprises a table generally indicated at 2, and a backboard 3, electrically connected together through a cable 4. Each backboard 3 is adapted to form an annunciator or indicator for designating the scores produced in playing the game, which results are shown electrically by the closing of switches at corresponding positions of the table 2, as hereinafter described.

Where a plurality of such game devices are associated with each other, as by being arranged in side-by-side relation as illustrated in Fig. 1, the several backboards 3 may be connected together electrically and to a timing device, generally indicated at 5, for controlling the action of all of them so as to regulate the maximum of play thereon, and manual control is provided by appropriate control switch 48.

The construction of the table 2 is shown more in detail in Figs. 2, 5, 6, and 7. This table comprises an enclosure in the form of a relatively flat box structure having a partition 6 therein, which partition is uniformly spaced from the top and bottom of the table 2, and forms a playing surface. A transparent cover 7 closes the top of the playing surface, being spaced above the partition 6 a distance sufficient to accommodate the movement of the ball or other missile therebetween.

The partition 6 is formed with a target area at one end portion thereof having a curved back wall 8 for directing the ball about the target area. The curved wall 8 forms a continuation of the outer side of a guide channel 9 that extends along one edge of the target area. At the lower end of the channel 9 is mounted a propelling plunger 10, spring-pressed in the usual manner of constructing such devices, so that upon retraction of the plunger manually, the spring will project the same under considerable force, thereby propelling the ball, indicated at 11 in Fig. 7, through the channel 9 with considerable force. The plunger 10 thus extends through the front wall of the casing of the table 2, in an accessible position, as shown in Fig. 2.

The target area on the partition or platform 6 is enclosed on the side opposite the curved wall 8 by an angular wall 12, provided adjacent the apex thereof, with an opening 13 through the partition or platform 6, to allow the ball to drop through this opening into the lower portion of the casing when it passes through the target area to the wall 12. It is preferable to have the partition 6 parallel with the transparent cover or glass 7, however, when the table is positioned on the counter 1 it is desirable to incline the table 2 so that the partition 6 is inclined toward the player so that the ball 11 will return by gravity toward the end of the table nearest the player. A sub-partition 6a is positioned immediately below the partition 6 and when the table is inclined in the position as shown in Fig. 8, the sub-partition 6a will have a slightly flatter angle than partition 6, but will be of such angle that the ball will return by gravity downward therealong until it engages an angularly disposed wall 30 to direct the ball 11 through an opening 6b in partition 6 so as to direct the ball into the original playing position in the lower end of channel 9. In the game as shown, only one ball is used, which ball automatically returns to position in the lower end of channel 9 to be re-played as soon as it can close the circuit by passing through the target area and

through one of the holes 18, unless the ball trap 31 is positioned to restrain the ball from entering channel 9 to be re-played, as will be more fully described hereinafter. If the ball fails to pass 5 through one of the holes 18, it will drop through the hole 13 without closing a circuit, and thus be returned to be replayed.

The target area on the platform or partition 6 is provided with a series of indicia, preferably 10 formed in shapes representing the respective suits of a deck of cards, such as "hearts," "clubs," "diamonds" and "spades," which are designated generally at 14 in Fig. 2. A row of upstanding pins 15 extends transversely across the target 15 area adjacent the indicia 14, forming abutments for obstructing the movement of the ball 11 onto the respective indicia. An additional upstanding pin is shown at 16 in the mid-portion of the target area adjacent the wall 8 to form an initial obstruction for the ball. A second row of upstanding pins 17 extends transversely across the target area adjacent the opposite edges of the indicia 14 to form further obstructions for the ball.

Intermediate the pins 15 and 17, openings 18 25 are formed through the platform or partition 6, five such openings 18 being provided in each indicia 14, in the form illustrated, for the purpose of representing and corresponding with the five highest playing cards of the corresponding suit, as the "ace," "king," "queen," "jack" and "ten."

Beneath the openings 18 are switch devices, as 30 shown in Figs. 5 and 6, adapted to be actuated by the ball 11 in dropping through the openings. One such switch device is provided for each opening for the purpose of energizing a circuit to an annunciator that will designate the particular opening through which the ball has dropped, and to energize a multi-point relay, such as is indicated by R in Figs. 9, 10 and 12.

A switch mechanism has been shown which has 40 spring contact 19, attached to the underside of the platform or partition 6, in position to be engaged by a contact 20, movable relative thereto and pivotally mounted at 21 on the underside of the partition 6. A spring 22 is connected with the movable contact 20 normally tending to maintain the contact in its full line position in Fig. 5, but adapted to yield for movement of the contact to its dotted line position therein when the projecting end 23 of the contact member is engaged by the ball dropping through the hole 18 therewith. This projecting end underlaps the hole, as shown in Figs. 5 and 6, in position to be engaged by the ball in dropping therethrough.

It is intended that the contact 20 should be maintained in closed position until the game is completed. Accordingly, I have provided an engaging finger 24, pivotally mounted at 25 on the underside of the partition 6 in overlapping relation with the projecting end 23 of the contact member, so that upon depressing of said end by engagement of the ball therewith, the finger 24 will drop to its dotted line position in Fig. 5, and hold the contact 20 in engagement with the spring contact 19.

At the conclusion of the game, the contacts can be released simultaneously by a bar 26, extending transversely over the projecting ends 23 70 of each set of contact members 20 in position for slidably engagement with the fingers 24, to return the fingers from their dotted line positions to their full line positions, thus releasing the contact members 20 and allowing the springs 22 attached thereto to restore the contacts 20 to their

full line position, breaking the circuits at the contacts 19-20.

The bars 26 for tripping the holding fingers 24 are adapted to be actuated simultaneously and are mounted on the underside of the platform 6. These bars are connected by cables 27 with a core 28 of a solenoid 29 mounted on the underside of the platform 6, so that upon energizing of the solenoid, the cables 27 will be actuated to move the bars 26 forward and disengage the trip arms 24, after which the bars 26 are returned to their normal positions by springs attached thereto.

On the sub-partition 6a of the casing of the table 2 is an inclined guideway 30, as shown in Figs. 2 and 7, in position to receive the ball 11 from the openings 13 and 18, for directing the ball back through the opening 6b and into the lower end of the channel 9. Arranged transversely of the guideway 30 is a trap door 31 connected with the core 32 of an electro-magnet 33. The magnet 33 acts, when energized, to project the door 31 into the path of the ball 11, when moved along the guideway 30, to trap the ball and prevent its entrance to the channel 9 at the completion of a game, as will be described more in detail hereinafter.

The backboard 3 constituting the annunciator includes a structure shown generally in Figs. 3 and 4, and diagrammatically in Fig. 11. This annunciator or backboard comprises a casing which is shown as having a door 34 on the front side thereof and hinged thereto for opening and closing movements. The casing contains a multiplicity of electric lamps, arranged in a suitable pattern, as desired, such as the radiating lines illustrated in the drawings. The number and disposition of these lamps will depend generally on the number of openings 18 provided in the indicia 14 on the target area of the table. The lamps in the respective rows are designated at 35, 36, 37, 38 and 39. A lamp 40 at the center of the group of lamps forms the point from which they radiate.

The lamp 40 is intended to represent the "joker" in the deck of playing cards and to be common to the respective rows of lamps. However, the lamps 35-39 which correspond with the cards represented by the respective openings 18 will indicate into which of the openings the ball has dropped. The five rows of lamps, in the form illustrated, correspond with the five holes in each of the indicia 14, one row corresponding with the "aces" of the respective suits; another row the "kings"; another row the "queens"; another row the "jacks"; and the fifth row the "tens." The suits of the cards are preferably arranged to form some symmetrical pattern; in the present instance they are formed into a star, with the same suit occupying the same outwardly spaced distance with respect to the center on each radial branch of the star, so that it is possible for the attendant to visually ascertain when a "flush" is lighted on the backboard. However, it is to be understood that other arrangements of the annunciator indicia, such as a square, circle or the like, may be used without departing from the spirit of the invention.

The lamps 35-40 are adapted to be enclosed in shields carried by the hinged door 34, as shown in Fig. 3. A center shield 41 is in position to cover the lamp 40 and groups of shields 42 are arranged in a pattern corresponding with the arrangement of the lamps 35-39. The

shields 41-42 are constructed of sufficient size and are opaque in the side walls thereof so as to enclose the interior of the shields against illumination passing into adjacent shields. Each of the shields 41-42, however, has a transparent or translucent cover face open to the front of the door 34, as indicated at 43 in Fig. 4, which transparent cover face 43 may be provided with indicia to indicate the particular card represented thereby.

Mounted upon the backboard 3 is an indicator lamp 44 adapted to indicate the completion of the game.

The wiring diagrams of the game device are illustrated in Figs. 11 and 12, from which the operation will be apparent.

The detail wiring diagram showing the circuits and the contact points to close the various legs of the circuits to register the winning combinations, is shown in Fig. 12. In order to more clearly illustrate the device, the suit and the indicia rank of each card have been indicated by the appropriate symbol of the suit and the appropriate letter or number designating the index of the card adjacent the particular diagrammatic point designated as "straights," the suits being indicated adjacent and in alignment with the transverse and longitudinal rows of contact points in the groups designated as "four of a kind" and "flushes," respectively, with the indicia adjacent the particular contact point.

The relay R, as shown in Fig. 9, has three sets of points 49, 50 and 51, each independently insulated from the others, so that upon closing one of the switches 19-20 a part of the leg of each of the circuits 53, 54 and 56 to 60, inclusive, will be closed toward completing a circuit through circuit 55 and through solenoid 33 of the ball trap and through "game complete" lamp 44 to the source of the current.

Each of the independent binding posts 62, 63 and 64 and each of the contact points 49, 50 and 51 are insulated from each other and are respectively connected to circuits 53, 54 and 56 to 60, inclusive. One of these relays is provided for each card shown and each time the relay closes a portion of each of the three circuits is closed and by the successive closing of the right combination of relay points in one of the three circuits designated as "four of a kind," "flush," or "straight," a circuit will be completed to light the "game complete" lamp which is in series with the solenoid 33 of the ball trap of the game table which is being played. The solenoids 33 of the ball traps of all the game tables are connected in parallel with the circuit 65. Likewise, the "game complete" circuit 55 of each table has connected in parallel therein the ball trap solenoid 33 of the circuit of each indicator backboard 3, as shown in Fig. 12 at 65a, by which arrangement the closing of the circuit 55 of the first table not only energizes the solenoid 33 of the ball trap of the first table but also energizes the solenoid of each of the other tables so as to close all of the ball traps simultaneously upon completion of any of the circuits of any of the tables.

A perfect score comprises four "aces" and the "joker." The "joker" will be indicated by the lamp 40, which is energized upon the closing of the switch 66 upon the starting of the game, being connected directly with the input circuit 45. In order to get a score comprising four "aces," it is necessary to project the ball successfully into the holes corresponding with the

"aces" of four different suits, one ball being used as many times as required or until the clock interrupts the circuit and clears the backboard 3, or until someone on another table completes a game by successfully projecting the ball 11 through holes 18 so as to give a winning combination of "four of a kind," "flush," or "straight."

The input circuit is connected with the respective lamps 35-39 through circuits generally indicated at 46, through a common supply circuit 47 which is connected to opposite sides of the circuit 46 through the switch formed by the contacts 19 and 20, as indicated in Figs. 11 and 12. Thus, when the ball drops into one of the openings 18 and closes the contact 20 against the contact 19, a circuit is completed from the source of supply 47 through the switch 19-20 and the circuit 46 to the corresponding lamps 35-39, causing energizing of the latter and energizing the relay R through lines connected to the binding posts 57 connected with the solenoid thereof. Each time a relay R closes, three sets of separately insulated points 49, 50 and 51 close a portion in each of the circuits of "four of a kind," "flush" and "straight." It is only necessary for four relays of any designated rank, such as four "aces" or four "kings" or the like to complete a circuit from the power supply line 45a through the circuits designated as "four of a kind" or "flush," the current branching off through line 52, as shown in Fig. 12, and following therewith until one of the lines 53 has all points closed so as to give a "four of a kind" game, or all of the points are closed on one of the lines 54. Upon the closing of the circuit 53 or 54 the current passes therethrough and on to line 55 which leads to the ball trap and to the "game complete" lamp 44 and returns through circuit 45b which indicates the completion of a game by energizing lamp 44.

If the relays are closed in such manner as to give a "straight," the current passes from line 45a through line 56 and through any of the successive relay points to line 57, thence to line 58 and through relay points and so on through 59, 60 and to 61 which joins with the circuit 55 leading to line 45b which closes the ball trap 33 and lights the "game complete" lamp 44 in a manner previously explained. When the game is completed a "game complete" lamp 44 will indicate such and the scoring will be indicated by the proper lights showing the winning combination. It is to be understood that many lamps may be lighted but only those that contribute toward closing a leg of circuits 53, 54, or 55 to 60 inclusive, contribute toward winning the game.

As an example, if the ball is first projected into the hole 18 representing the "ace of hearts," a circuit is completed to one of the lamps 35, causing the latter to be energized. The second ball may pass into the hole corresponding with the "ace of clubs," closing the circuit to the second lamp 35. The third ball in like manner would close a circuit to the third lamp 35, indicating the "ace of diamonds," and the fourth ball likewise indicates the "ace of spades." This would complete the perfect game and upon the conclusion thereof a circuit would be completed through the points 49 of the several relays R and to the lamp 44 to indicate the completion of the game, also actuating the solenoid 33 to trap all outstanding balls 11.

Other winning games may be indicated according to the positions where the ball may fall successively through the several holes 18, as all

"aces," "kings," "queens," "jacks" or "tens" respectively of all suits of cards, or representing a "straight," as "ace," "king," "queen," "jack," and "ten" all of the same suit, such as "spades," "diamonds," "clubs" or "hearts."

Three accumulating circuits have been shown in Figs. 11 and 12, although different combinations or additional circuits of substantially the same arrangement are considered within the scope of the present invention.

The circuits 46 are connected with respective lamps 35-39 and within the circuit 46 is the solenoid of relay R having multiple contacts 49, 50 and 51 thereon and separately insulated therefrom so as to close any one of the legs 53, 54 or 55 to 60 so as to give the correct action upon the "game complete" lamp 44 and the solenoid 33 of the ball trap.

At the completion of the game or after a definite time interval, the board may be cleared by de-energizing the supply circuit thereof by the switch 66, although it is preferred to actuate the electromagnet 29 to trip the fingers 24, as described above, and thereby reset the switches 19-20. This may be done manually by a switch 43, or by the master clock control 5, after a definite interval of time. The clock control 5 may serve also, if desired, to control a plurality of game devices, as indicated in Fig. 1, which may be operated simultaneously by different players.

While the game has been described in detail with respect to operating multiple units simultaneously by several players, it is to be understood that each game unit may be played independently of the others and the same scoring results obtained, and it may also be adapted for use with conventional coin-chute equipment to actuate the re-set switch 48 and either the game played with a single ball, as above described, or it may be played with a plurality of balls.

While the invention has been illustrated and described in one embodiment thereof, it is to be recognized that variations and changes may be made therein without departing from the invention, as specified in the claims.

I claim:

1. A game device of the character described comprising a target area, indicia thereon representing respective suits of playing cards, a plurality of circuit closers adjacent each of the indicia to represent respective cards of each suit and in position to be closed by a missile projected over the target area, and an annunciator including a plurality of sets of signalling devices corresponding respectively with the respective playing cards of the several suits and connected by electric circuits with the circuit closers to indicate thereon winning groups of cards upon closing of the corresponding circuits to the signalling devices.

2. In a game device of the character described, the combination of a target area adapted to receive a missile projected thereover and including a plurality of indicia to represent respective suits of a deck of playing cards, each of said indicia having a plurality of circuit closing devices adjacent thereto to represent respective cards of each suit and each circuit closing device having a contact closing member adapted for engagement thereof by the missile to be moved to a circuit closing position, an annunciator including a plurality of groups of signalling devices corresponding with the respective cards of the several suits and electrically connected with the circuit closing devices of said circuits to indicate

the closing of the circuit closing devices upon engagement by the missile.

3. In a game device of the character described, the combination of a target area adapted to receive a missile projected thereover and including a plurality of indicia to represent respective suits of a deck of playing cards, each of said indicia having a plurality of circuit closing devices adjacent thereto to represent respective cards of each suit and each circuit closing device having a contact closing member adapted for engagement thereof by the missile to be moved to a circuit closing position, an annunciator including a plurality of groups of signalling devices corresponding with the respective cards of the several suits and electrically connected with the circuit closing devices of said circuits to indicate the closing of the circuit closing devices upon engagement by the missile, and means for connecting said indicating devices together in a circuit arranged to indicate four cards of a kind in different suits.

4. In a game device of the character described, the combination of a target area adapted to receive a missile projected thereover and including a plurality of indicia to represent respective suits of a deck of playing cards, each of said indicia having a plurality of circuit closing devices adjacent thereto to represent respective cards of each suit and each circuit closing device having a contact closing member adapted for engagement thereof by the missile to be moved to a circuit closing position, an annunciator including a plurality of groups of signalling devices corresponding with the respective cards of the several suits and electrically connected with the circuit closing devices of said circuits to indicate the closing of the circuit closing devices upon engagement by the missile, and means for connecting said indicating devices together in a circuit arranged to indicate a flush of the playing cards.

5. In a game device of the character described, the combination of a target area adapted to receive a missile projected thereover and including a plurality of indicia to represent respective suits of a deck of playing cards, each of said indicia having a plurality of circuit closing devices adjacent thereto to represent respective cards of each suit and each circuit closing device having a contact closing member adapted for engagement thereof by the missile to be moved to a circuit closing position, an annunciator including a plurality of groups of signalling devices corresponding with the respective cards of the several suits and electrically connected with the circuit closing devices of said circuits to indicate the closing of the circuit closing devices upon engagement by the missile, and means for connecting said indicating devices together in a circuit arranged to indicate successive cards of different values.

6. A game device of the character described comprising a target area, indicia thereon representing respective suits of playing cards, a plurality of circuit closers adjacent each of the indicia to represent respective cards of each suit and adapted to be closed by a missile projected over the target area, an annunciator including a multi-point relay, a plurality of sets of signalling devices corresponding respectively with the respective playing cards of the several suits, electric circuits connecting said signalling devices with the circuit closers and including the multi-point

relay to close a portion of a plurality of circuits, and means connected with said last mentioned circuits to indicate a winning group of cards upon the completion of any of said circuits.

5 7. A game device of the character described comprising a target area, indicia thereon representing respective suits of playing cards, a plurality of circuit closers adjacent each of the indicia to represent respective cards of each suit and adapted to be closed by a missile projected over the target area, an annunciator including a multi-point relay, a plurality of sets of signalling devices corresponding respectively with the respective playing cards of the several suits, electric circuits connecting said signalling devices with the circuit closers and including the multi-point relay to close a portion of a plurality of circuits, means connected with said last mentioned circuits to indicate a winning group of cards upon the completion of any of said circuits, and means for trapping said missile upon completion of one of said circuits.

25 8. In a game device of the character described, the combination of a target area adapted to receive a missile projected thereover and including a plurality of indicia to represent respective suits of a deck of playing cards, a plurality of circuit closing devices adjacent the indicia, an annunciator including a plurality of groups of signalling devices adapted to represent the respective suits of the playing cards and the respective cards of each suit, electric circuits connecting the first-mentioned circuit closing devices with the signalling devices and controlled by said 30 circuit closing devices, and a plurality of groups of circuit closers, each group comprising a plurality of sets, auxiliary circuits connected with said groups of circuit closers and connected with said annunciator, one group having each of the sets of said circuit closers adapted to represent the corresponding cards in all the suits of the 35 target area indicia, said sets being connected in parallel circuits, and a second group having each of the sets of said circuit closers adapted to represent the corresponding cards in all the suits of the target area indicia, the circuit closers of each set of the last-mentioned group being connected in parallel and the several sets thereof being connected in a series circuit.
